UNITED STATES PATENT OFFICE.

JEAN ALBERT PERONY, OF ST.-OUEEN, FRANCE, ASSIGNOR TO SOCIETE D'OUTILLAGE
MECANIQUE ET D'USINAGE D'ARTILLERIE, OF ST.-OUEEN, SEINE, FRANCE, A LIMITED
JOINT-STOCK COMPANY OF FRANCE.

PLATE-BENDING PRESS.

1,422,779.

Specification of Letters Patent. Patented July 11, 1922.

Application filed July 21, 1920. Serial No. 398,019.

To all whom it may concern:

Be it known that I, JEAN ALBERT PERONY, a citizen of the Republic of France, resident of St.-Ouen, Seine, France, have invented 5 new and useful Improvements in Plate-Bending Presses, which invention is fully set forth in the following specification.

Plate-bending presses are known wherein the plate is placed vertically. In those machines the bending is effected by the motion 10 of a vertical press-head or beam movable horizontally so as to force the plate against a fixed vertical abutment block.

The present invention has for its object to 15 provide an improved bending press of this type, which, compared with the known presses has the following advantages:—

1. The improved press comprises only two main parts which are of minimum weight 20 and bulk.

2. The movable press-head is guided firmly in the fixed abutment block, whereby it is assured of great stability even when the top driving member of the said press-head is detached for the purpose of removing the bent 25 plate.

3. This driving member is jointed in such a manner that it can be lifted off and replaced in position without any necessity for 30 altering the adjustment of its length.

4. The effort exerted by the press is small at the beginning of the bending operation and becomes a maximum at the end of each such operation thus effecting a saving in the 35 power consumed.

According to the present invention the improved plate-bending press comprises a fixed abutment block and a movable press-head provided with a foot which is adapted 40 to slide in the fixed abutment block and which gives great stability to the said press-head. The relative displacement between the movable press-head and the fixed abutment block is produced by the action, upon eccentric 45 journals, of two axles rotating respectively in the movable press-head and in its top driving member. These axles which are driven horizontally and are coupled together by their actuating members, are operated by a hydraulic ram or any other suitable means.

A constructional form of this invention is

illustrated by way of example in the accompanying drawings in which:—

Fig. 1 is a longitudinal side elevation of 55 the improved plate-bending press, showing the movable press-head in its farthest position from the fixed abutment block.

Fig. 2 is a vertical section taken along the axis of the press. 60

Fig. 3 is a plan of the top of the press.

Fig. 4 is a horizontal section on the line 4—4 of Fig. 1.

Fig. 5 is a vertical section on the line 5—5 of Fig. 3. 65

In Figs. 1 to 5 inclusive, the movable press-head is in its farthest position from the fixed abutment block.

Fig. 6 is a section similar to Fig. 5, showing the movable press-head in its nearest 70 position to the fixed abutment block.

Fig. 7 is a vertical cross section on the line 7—7 of Fig. 1.

In the above figures A is the fixed bending member or abutment block made in one 75 piece with the bedplate A¹. B is the movable bending member or press-head; it is provided at its underside with a guide flange or foot B¹ resting on the bedplate A¹. This foot B¹ slides by means of a nose B² in 80 a bottom recess or guide portion a² of the fixed abutment block A. In other words, the movable press-head has the shape of an angle bar whose vertical flange constitutes the tool proper, (the press-head) by means 85 of its edge b, whereas the horizontal flange B¹—B² is guided by its nose B² in a recess a² of the fixed abutment block A—A¹.

C and C¹ are axles formed at their ends with eccentric journals c c and c¹ c¹ respectively; they serve for driving the movable press-head at its top and bottom ends. 90

The bottom axle C¹ rotates in the nose B² of the movable press-head, whereas its journals c¹ revolve, each in a slide block D¹ which is incapable of moving horizontally, but is able to move vertically in a slideway A² of the fixed abutment block A. 95

The top axle C rotates in the top driving member proper consisting of a tie-rod E 100 which is engaged by means of an eye e on a top projection b¹ of the movable press-head B. The side journals c revolve, like the journals c¹, each in a side block D which cannot

move horizontally, but is capable of vertical motion in a slideway A^3 formed on the fixed abutment block A.

The foot B^1 and the tie-rod E provide 5 connections between the fixed bending member or abutment block A and the movable bending member or press head B, and relative movement between said members is effected by the axles C and C^1 which are 10 eccentrically journaled in the abutment and the tie-rod E and foot B^1 , respectively.

On the two axles C, C^1 there are fixed 15 levers H, H^1 which are parallel to each other and are coupled together by connecting rods J. Moreover, each side journal c is kept at a constant distance from the corresponding journal c^1 by a stay rod K.

The displacements of the movable press-head may be produced hydraulically by a 20 plunger L working in a fixed cylinder M and acting upon the levers H through the medium of links N.

For the purpose of allowing of the removal of the plate after it has been bent, 25 the tie-rod E is arranged to be movable around the top axle C. The rotational motion of the tie-rod E is produced hydraulically by the action of a plunger P working in a cylinder R and coupled to the tie-rod 30 E by two links S.

The operation of the improved plate-bending press is as follows:—

On pressure water being admitted into the hydraulic cylinder M, the plunger L will 35 move down and act through the links N upon the bottom levers H^1 which will in their turn act through the connecting rods J upon the top levers H. The levers H, H^1 fixed on the journals c, c^1 , compel the axles 40 C and C^1 to rotate together. During this movement the bottom axle C^1 remains at a constant height, but moves horizontally and thus drives the movable press-head B. The eccentric side journals c^1 move vertically and 45 compel the side journals c of the top axle C to move through an equal vertical distance.

The result of this is that the top axle C remains at a constant height and displaces 50 itself horizontally, moving with it through the tie-rod E, the upper part of the movable press-head B. The movements of the two axles C, C^1 being exactly similar to each other, the movable press-head B will be displaced parallelly to itself, and the tool b will compel the plate to enter the cavity a constituting the matrix, in the fixed abutment block A.

When the stroke has been completed, the 60 hydraulic plunger L is caused to move in the reverse direction, and the axles C, C^1 thereby receive a movement that is the reverse of the preceding movement, and causes

the movable press-head B to move away from the fixed abutment block A. In this 65 movement away, the movable press-head B is always being displaced parallelly to itself.

When the bending of the plate is completed, the pressure water is admitted to the plunger P which, through the medium of 70 the connecting rods S, causes the tie-rod E to turn on the central journal of the top axle C for the purpose of bringing it into the position indicated in dot-and-dash lines in Fig. 1.

The plate can then be removed, and by causing the plunger P to act in the reverse direction, the tie-rod E can then be returned into its operative position. When the tie-rod E is lifted, the movable press-head B 80 has nevertheless great stability by reason of its bottom guidance, and therefore any handling of the plate may be done without detriment to the stability of the press.

It is to be understood that the hydraulic 85 drive (M—L) of the levers H, may be replaced by any other suitable drive. Similarly the turning movement of the tie-rod E around the axle C, may be produced by a means other than the one shown by way 90 of example.

Having now particularly described and ascertained the nature of my said invention and in what manner the same is to be performed, I declare that what I claim is:—

1. A plate bending press comprising a fixed abutment block provided with a recessed guide portion, an angularly formed press head having one side shaped to provide a bending tool and the other side 100 formed to provide a flange engaging in the recessed guide portion of said abutment block, and means adapted to impart parallel reciprocating motion to the press head with respect to the abutment block, said means including a tie rod operatively connected with said press head and axles journaled in the abutment block and extending through said tie rod and the flange of said press head respectively.

2. A plate bending press comprising a rigid abutment and a movable press head, and means adapted to impart parallel reciprocating motion to said press head with respect to the abutment, said means comprising a pair of slide blocks movably guided in the abutment, a pair of axles eccentrically journaled in said slide blocks and operatively connected with the press head, a source of power, and operative connections between said source of power and the axles.

Dated this 28th day of May, 1920.

In testimony whereof I have signed this specification.

JEAN ALBERT PERONY.
